UNITED STATES PATENT OFFICE.

COLBURN N. CHRISTOFFERSON AND JOHN F. LINDBERG, OF HIBBING,
MINNESOTA.

WINDOW-WASHER'S PLATFORM.

No. 823,921.

Specification of Letters Patent.

Patented June 19, 1906.

Application filed November 20, 1905. Serial No. 288,204

To all whom it may concern:

Be it known that we, COLBURN N. CHRISTOFFERSON and JOHN F. LINDBERG, citizens of the United States, residing at Hibbing, in the county of St. Louis and State of Minnesota, have invented certain new and useful Improvements in Window-Washers' Platforms, of which the following is a specification.

- 10 The object of our invention is to provide an improved platform or stage designed to be detachably secured to and extend outwardly from a window-casing for the convenient use of window-washers, painters, or the like and which embodies an improved construction whereby it is adaptable as a ready attachment for windows of different widths and the casings or walls of which are of different thicknesses.
- 20 For a full description of the invention and the merits thereof and also to acquire a knowledge of the details of construction of the means for effecting the result reference is to be had to the following description and accompanying drawings, in which—

25 Figure 1 is a plan view of our improved platform. Fig. 2 is a side elevation thereof. Fig. 3 is a vertical section showing the attachment of the platform in operative position within a window-casing which is also shown partly in section. Fig. 4 is a horizontal sectional view of the said casing, showing a portion of the platform in the window in plan view. Fig. 5 is a detail view.

35 Corresponding and like parts are referred to in the following description and indicated in all the views of the drawings by the same reference characters.

The platform proper, 1, in the present instance comprises a suitable number of boards laid transversely upon and attached at their ends to longitudinally-extending stringers 2. Intermediate their ends the said stringers 2 have attached thereto downwardly-extending legs 3, the lower ends of which are preferably beveled, as shown at 3^a, to conform to the inclination of the window-sill on which they are designed to rest. The legs 3 are preferably braced by diagonal struts 4, which are secured at one end thereto and at their other ends to the under side of the stringers 2, near the outer ends of the latter. Preferably metallic strips or bands 5 are secured to the

upper surface of the transverse boards of the platform proper, 1, and extend rearwardly 55 therebeyond and are provided at their rear ends with downward and returned portions or extremities 5^a, which are secured to the lower side of the stringers 2 at the rear ends of the latter by bolts 5^b, this construction of 60 the strips or bands 5 providing elongated openings from the rear edge of the rearmost board to the downwardly-extending portions 5^a. Besides the struts 4 the platform 1 and the legs 3 are in the present instance suitably 65 braced, as shown at 6 and 7, the braces 6 converging toward each other and being secured to the under surface of the platform 1 at their forward ends and also being secured at their other ends to the rear ends of the stringers 2. 70

8 designates a transversely-extending bar which is constructed in two sections 8^a and 8^b, having their ends overlapped with a scarf-joint and arranged for extensible movement with respect to each other. The lapping end 75 of each section is preferably provided with a metallic bearing-strip 9, having at one end a lug or projection 9^a, and a clamp 10 surrounds the two overlapping ends of the sections 8^a and 8^b and is provided with a clamp-screw 10^a, designed to impinge against one of the bearing-strips 9 and arranged to be tightened to hold the two sections of the transverse bar 8 in more or less extended position with respect to each other. The lugs 80 or projections 9^a of the two bearing-strips are designed to abut against said clamp to limit the movement of said sections in one direction.

The bar 8 projects at each end through the 90 elongated openings provided at the rear ends of the bands 5 and is free to move through said openings between the bands and the adjacent portions of the stringers 2, and each projected end of the bar 8 is provided at top 95 and bottom with a plate 11 and with an angular socket 12 between said plates, the said plates forming a bearing between which is pivotally secured one end of a link 13. The other end of each of said links 13 is in turn 100 pivotally secured between the respective band 5 and the adjacent portion of the stringer 2, preferably by the same bolt 5^b that connects said band to the stringer.

In the practical application of our invention the platform is extended from the win-

dow-casing with the lower beveled ends of the legs 3 resting upon the window-sill A and with the legs abutting against the outer edge of the window-stool B. To maintain the platform from tilting downwardly and outwardly by its own weight or by the weight of the person standing thereon, we have provided the improved construction of extensible bar 8, hereinbefore described, and in the application of the device to the window-casing the screw 10^a of the clamp 10 is loosened sufficiently to allow the sections of said bar to be extended so that the projecting ends will bear against the inner sides of the window-casing C, whereupon the said clamp is again tightened and the entire device is thus held securely in an operative position.

Having thus described the invention, what is claimed as new is—

1. A device of the character described, comprising a platform, supports therefor, a laterally-extending extensible bar connected to said platform, and means whereby the extension of said bar will effect its movement away from said support and vice versa.

2. A device of the character described comprising a platform provided with supporting-legs, a laterally-extending extensible bar, and a pivotal connection between the platform and the sections of said bar whereby as the same is extended it will move away from the legs and vice versa.

3. A device of the character described comprising a platform, stringers embodied therein, supporting-legs connected to said platform, longitudinally-extending bands secured to said platform and stringers and providing at their rear ends elongated openings, an extensible sectional bar mounted to move

through said openings, and links connecting the sections of said bar with the said stringers.

4. A device of the character described comprising a platform including longitudinally-extending stringers, legs secured to said stringers, bands secured to said platform and providing at their rear ends suitable openings, a transversely-extending sectional bar provided with overlapping ends, means for clamping the sections of said bar in differently-extended positions, and links pivotally connecting the ends of said bar with said stringers, said ends working through said openings.

5. A platform for the purpose set forth, comprising a platform proper embodying longitudinally-extending stringers, bands secured to said stringers and providing at their rear ends elongated openings, a transversely-extending sectional bar having overlapping ends, a clamping-band arranged to hold said sections in different extended positions, the ends of said sections working through the openings provided by said bands and provided at top and bottom with attaching-plates, and links pivotally mounted between said plates at one end and to the stringers at the other ends, whereby the movement of said sections with respect to each other will simultaneously move the bar as a whole in a direction at right angles to the movement of extension.

In testimony whereof we affix our signatures in presence of two witnesses.
